UNITED STATES PATENT OFFICE

2,198,452

AUTOMATIC VENT DEVICE

Milton Lipschitz, Jersey City, N. J.

Application December 31, 1938, Serial No. 248,714

6 Claims. (Cl. 137—122)

The invention relates to venting means for permitting the escape of entrapped air from radiators of heating systems, particularly the usual hot water heating systems. Heretofore, it has been the usual practice to manually open or remove a vent connection of a radiator of the system to clear the former of the entrapped air, which operation no only was troublesome and inconvenient but resulted frequently in spillage of water.

The present invention has for an object to provide means whereby the entrapped air will escape automatically from a radiator to which the device is attached.

15 A further object of the invention is to provide a novel construction of venting device whereby the venting is accomplished in a simple and effective manner, the device withal being readily and economically manufactured and installed.

20 In carrying out the invention, the novel venting means is constructed in the form of a shell or container designed for attachment at the upper portion of a radiator to afford communication between the latter and the shell at its lower portion 25 or bottom. At the top, the shell is provided with a valve-controlled outlet designed to prevent leakage from the radiator as well as entrance of air thereto when water or steam is withdrawn from the radiator or a portion thereof. This 30 shell, moreover, affords a float chamber for a float suitably mounted therein to move vertically of the shell.

The float in turn is designed to engage a tubular flexible and collapsible element whose one 35 end is connected with the valve controlled outlet and whose other end is positioned in the upper portion of the shell interior to remove from the same air entrapped in a radiator to which the shell is connected. Provision is made for collapsing 40 this tube at one or more portions and in a manner such that only a slight force is required to effect a complete shut-off of the communication between the interior of the shell and the outlet thereof. This is effected by providing the 45 closure at a point removed more or less from the point of engagement of the float with the said tube, for example, by bending or kinking the tube at a point intermediate its length.

The nature of the invention, however, will best 50 be understood when described in connection with the accompanying drawing, in which:

Fig. 1 is a vertical section through the novel venting device as attached to a radiator coil, a portion of which is also shown in vertical section.

55 Fig. 2 is a vertical section of the device and

shows the float in position for sealing the device against external atmosphere when the air has been substantially expelled thereby from the radiator.

Figs. 3 and 4 are vertical sections showing a 5 modified form of the device, Fig. 3 illustrating the position of the elements during the venting action, and Fig. 4 the position of the elements for sealing the communication to the external atmosphere.

10 Referring to the drawing, 10 designates a coil or column of a radiator, for example, of a hot water heating system, in which case water will occupy substantially the interior of the column during normal operation. However, in view of 15 the fact that water usually holds by absorption more or less air, which is released in the radiator as the water circulates, such air will collect in the upper portion of the radiator, more especially in the end column or coil thereof. When a 20 substantial portion of the radiator thus becomes filled with air, the efficiency of the heating or radiating surface is accordingly diminished and it becomes necessary from time to time to vent the radiator of this entrapped air. In the embodiment illustrated, such air is indicated, Fig. 1, as 25 above the level 11 of the water therein.

The novel device for automatically venting this air is shown as attached to the upper portion of the column 10 by a suitable fitting 12, said device 30 comprising the shell 15 communicating at the bottom through said fitting with the column and having a removable top 16 screwed thereon and carrying a valve-controlled outlet 17. The latter 35 embodies a tube 18 threaded at its outer end to receive a screw cap 19 provided with an aperture 20 for discharge of air from the interior of the shell 15, as hereinafter set forth. Tube 18 carries 40 also a bushing affording a valve seat 21 from which extends inwardly into the upper portion of the interior of shell 15 a rigid outlet tube 22.

As indicated in Fig. 1 of the drawing, a valve piece, as the ball 23, normally seats in the valve seat 21 to close off the communication between the interior of shell 15 and the cap 19, thus sealing 45 the shell; and in Fig. 3 a needle valve 24 guided in the cap 25 serves the same purpose. Needle valve 24, moreover, is provided with a flange 26 in proximity to the top of the cap to limit outward excursion of the valve, as well as to permit 50 screwing down the valve tightly in its seat to positively seal the shell should it be desired for any reason to permanently shut off communication with the external atmosphere. This may conveniently be effected by screwing down cap 25 55

whose top then shoulders against the flange 26. In the embodiment illustrated in Fig. 1, the ball 23 may be similarly locked through engagement therewith of a rod 27, attached to the cap 19, 5 when said cap is screwed down upon the tube 18.

A bracket 30 is also carried by the top 16 within the upper portion of the shell 15, and there depends therefrom a suitable vertical guide as the U-shaped member 31 extending substantially 10 to the bottom of the shell and affording a guide and bottom stop for a float 32. This float will rise or fall vertically of the shell in accordance with the level of the water therein as received from column 10.

15 To vent the air, there is attached to the tube 22 a further but flexible and collapsible tube 35 as of rubber or other flexible material which may be collapsed by kinking the same. The free end 36 of this tube is positioned in the upper end 20 of the shell, as indicated, so that air within the shell will be expelled therefrom under pressure of the advancing water in the radiating device, through the valve 21—23 and aperture 20 of the cap 19. When the required volume has been thus 25 removed, which will occur when the water reaches the device and thereby raises float 32, as indicated in Fig. 2, provision must be made to close off communication through tube 35.

In accordance with the invention, this is effected, not by direct pressure of the float member against the tube to constrict a portion thereof, but by utilizing the movement of the float more quickly and with greater force to effect a collapse of the tube at one or more portions thereof. Thus, the tube is bent as at 37, Fig. 1, or 30 formed into a circular portion 38, Fig. 3, and the bent or circular portions will be quickly kinked or doubled through the substantial leverage afforded as the float rises in the shell. In the 35 former instance, a kink 39, Fig. 2, is provided in the tube and serves to seal off effectively the shell from external communication; and in the latter embodiment, two kinks 40 and 41, Fig. 4, are provided in the tube to doubly insure such 40 sealing. As the float recedes, the tube resumes its normal form, to afford communication therethrough. However, access to the interior of the shell will be blocked at the valve 21—23, or by the valve stem 24, as the case may be, so that 45 air may not be drawn into the heating system.

50 I claim:

1. A float valve for radiators of a heating system, comprising a shell having a radiator connection at the bottom and provided with a vent 55 outlet at the top, and float means mounted for vertical movement within the shell, a rigid support member carried by the shell to afford an abutment element within its upper portion, and a tube of resilient and collapsible material located 60 within the shell and carried by said support member, one end of the tube being connected with the vent outlet and its other end being located by said support member at the uppermost portion of the shell, an intermediate portion of the tube being located between said support member abutment and the top of the float means which is 65 adapted for engagement therewith to press the same toward the abutment for collapsing the tube at a point removed from the point of engagement of the float therewith.

70 2. A float valve for radiators of a heating system, comprising a shell having a radiator connection at the bottom and provided with a vent outlet at the top, and float means mounted for vertical movement within the shell, a rigid 75 supporting bracket attached to the upper por-

tion of the shell and having an arm extending transversely thereof in proximity to the top of the float means, and a tube of resilient and collapsible material carried by said bracket, one end of the tube being connected with the vent outlet 5 and its other end retained by said bracket in the uppermost portion of the shell and opening to the interior thereof, an intermediate portion of the tube being held to the arm of the bracket between the same and the top of the float means 10 which is adapted for engagement therewith to press the same toward the bracket arm for collapsing the tube at a point removed from the point of engagement of the float therewith.

15 3. A float valve for radiators of a heating system, comprising a shell having a radiator connection at the bottom and provided with a vent outlet at the top, and float means mounted for vertical movement within the shell, a rigid supporting bracket attached to the upper portion 20 of the shell and having an arm extending transversely thereof in proximity to the top of the float means, and a tube of resilient and collapsible material doubled upon itself and carried by said bracket, one end being connected with the 25 vent outlet and the other retained by the bracket in the uppermost portion of the shell and opening to the interior thereof, the doubled portion of the tube being located between the bracket arm and the top of the float means which is adapted 30 for engagement therewith to press the same toward the bracket arm for collapsing the tube at a point removed from the point of engagement of the float therewith.

35 4. A float valve for radiators of a heating system, comprising a shell having a radiator connection at the bottom and provided with a vent outlet at the top, and float means mounted for vertical movement within the shell, a rigid supporting bracket attached to the upper portion of 40 the shell and having an arm extending transversely thereof in proximity to the top of the float means, and a tube of resilient and collapsible material carried by said bracket, one end of the tube being connected with the vent 45 outlet and its other end passing through the bracket and terminating in the uppermost portion of the shell and opening to the interior thereof, an intermediate portion of the tube being located between the bracket arm and the top of the float means which is adapted for engagement 50 therewith to press the same toward the bracket arm for collapsing the tube at a point removed from the point of engagement of the float therewith.

55 5. A float valve for radiators of a heating system, comprising a shell having a radiator connection at the bottom and provided with a vent outlet at the top, and float means mounted for vertical movement within the shell, a rigid support member carried by the shell to afford an abutment element within its upper portion and having a downwardly directed rod extension passing longitudinally of the float means for guiding the latter in its vertical movement, and a tube 60 of resilient and collapsible material located within the shell and carried by said support member, one end of the tube being connected with the vent outlet and its other end being located by said support member at the uppermost portion 65 of the shell, an intermediate portion of the tube being located between said support member abutment and the top of the float means which is adapted for engagement therewith to press the same toward the abutment for collapsing the tube 70

75

at a point removed from the point of engagement of the float therewith.

6. A float valve for radiators of a heating system, comprising a shell having a radiator connection at the bottom and provided with a vent outlet at the top, and float means mounted for vertical movement within the shell, a rigid support member carried by the shell and having an arm extending transversely thereof in proximity 5 to the top of the float means and also a rod extension downwardly directed from the arm and passing longitudinally of the float means for guiding the latter in its vertical movement, said arm affording an abutment element within the upper portion of the shell, and a tube of resilient and collapsible material located within the shell and carried by said support member, one end of the tube being connected with the vent outlet and its other end being located by said support member at the uppermost portion of the shell, an intermediate portion of the tube being located between said transversely extending arm and the top of the float means which is adapted for engagement therewith to press the same toward 10 the abutment for collapsing the tube at a point removed from the point of engagement of the float therewith. 10
